UNITED STATES PATENT OFFICE

EDWARD M. SPLAINE, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS

OPHTHALMIC MOUNTING

Application filed September 24, 1929. Serial No. 394,773.

This invention relates to improvements in ophthalmic mountings and has particular reference to an improved spring connection for said mountings.

5 The principal object of the invention is to provide an improved connection for a detachable spring bridge for an ophthalmic mounting.

10 Another object of the invention is to provide a detachable spring which may be quickly and rigidly secured to an ophthalmic mounting and which will not become loose during its continued use.

15 Another object is to simplify the bridge connection in ophthalmic mountings, particularly mountings requiring pivoted bridge springs.

20 Another object of the invention is to provide improved means for taking up loose play and wear in spring bridge connections for ophthalmic mountings, particularly in interchangeable spring bridge connections.

25 Other objects and advantages of the invention will be apparent from the following description taken in connection with the accompanying drawing, and it will be understood that many changes may be made in the details of construction and arrangement of parts without departing from the spirit of 30 the invention as expressed in the accompanying claims. I, therefore, do not wish to be limited to the exact details shown and described as the preferred form only has been shown by way of illustration.

35 Referring to the drawing:

Fig. I is a front elevation of an ophthalmic mounting embodying the invention.

Fig. II shows the mounting in folded or closed position.

40 Fig. III is a fragmentary enlarged view of the spring connection shown partly in cross section.

Fig. IV is a fragmentary plan view of a portion of the spring connection shown in 45 Fig. III.

Fig. V is a cross section on line V—V of Fig. III.

50 Spring bridges are adapted to be used with an ophthalmic mounting commonly known as the folding Oxford or other generally

similar eyeglasses. The pivoted bridge spring of such mountings usually comprises spring pivotal connections at each end of the bridge spring of precious metal and by detachably connecting the bridge spring with 55 its pivot connection repairs are greatly facilitated in case of the breakage of the spring, thereby reducing the cost of parts and repairs. Several attempts have been made to accomplish this result, many of which have 60 been impractical because of the continual wear of parts during their use, which soon resulted in a loose, wobbly connection, and others of which were impractical because too much time was required to interchange the 65 parts, many of which required special tools.

The present invention obviates these difficulties and inconveniences by providing adjustable means for eliminating looseness and to compensate for wear of parts. The device 70 is simple in construction and is easily and quickly interchanged.

Referring more particularly to the drawing, the illustrative embodiment of the invention comprises the lenses 1 mounted in the 75 lens frames 2 connected by the bridge spring 3. Nose guards 4, as indicated, may be mounted on suitable posts secured to the lens frames 2. The bridge spring 3 is provided at each end with a spring pivot connection 5 to 80 allow the mounting to be folded, as illustrated in Fig. II. Under these conditions a notch 6 may be made in a suitable enlargement 7 on one of the lens frames 2 to be engaged by a spring catch or other means 23 85 carried by the handle 8. The mounting is thus retained in folded position until a suitable catch button or the like 24 is retracted to release the spring catch to allow the ophthalmic mounting to automatically snap open 90 under the action of the spring 3.

As illustrated in greater detail in Fig. III, the spring pivot connections 5 at each end of the bridge spring 3 comprise a pivot casing 9 which may substantially enclose the pivot 95 knuckle 10 formed on the lens frame 2. The casing 9 is pivotally secured to the knuckle 10 by the screw or like means 11. The said casing is provided with a grooved portion 12 adapted to receive the perforated end of the 100

spring 3, and is provided adjacent one end thereof with a tapered portion 13 adapted to engage a lug 14 carried by the spring 3. The lug 14 is provided with a shouldered head 15 which has a tapered undercut portion 16 with which the tapered portion 13 of the casing 9 interlocks. The tapered portion 13 and lug 14 are held in constant engagement with each other by a screw or like means 17 which secures the spring 3 to the casing. The lug 14 is secured to the spring 3 by heading over the portion 18 which extends through an opening formed in the spring.

The lens frames 2 are split at 19 to permit the removal and replacement of lenses. A screw or like means 20 is adapted to close the split and hold the lens in the frame.

By reference to Fig. III, it will be seen that a slight clearance 21 is formed between casing 9 and the end of the spring 3 adjacent the screw connection 17 to allow the lug 14 and the end 13 of the casing 9 to be rigidly drawn together and also to take up any wear or loose play at that connection. It will be seen that the spring 3 may be quickly interchanged by simply removing the screw 17 and sliding the lug 14 free of the tapered end 13. To secure the spring 3 in position the screw 17 is tightened until the parts are drawn rigidly together. The tapered end 13 of the casing 9 and the tapered lug 14 provide a simple interchangeable connection wherein loose play and wear of parts may be quickly removed and compensated for by simply tightening the screw 17.

From the foregoing description it will be seen that I have provided simple, economical and efficacious means of forming an interchangeable bridge spring for an ophthalmic mounting wherein the spring may be quickly and rigidly secured to the mounting.

Having described my invention, I claim:

1. An interchangeable spring bridge for an ophthalmic mounting comprising a spring member having perforations adjacent its ends and intermediate its ends and lugs in the intermediate perforations having tapered undercut portions.

2. In a device of the character described in combination with the lens holding means of an ophthalmic mounting, a projecting member on the lens holding means having a tapered portion adjacent its free end, means for connecting the lens holding means together, a lug on the connecting means having a tapered undercut portion in engagement with the tapered end of the projecting member and means for securing the connecting means to the projecting member to hold the tapered undercut lug in engagement with the tapered end of said projecting member.

3. In a device of the character described in combination with the lens holding means of an ophthalmic mounting, a projecting member pivoted to the lens holding means and

having a tapered notched portion adjacent its free end, resilient means for connecting the lens holding means together, a lug on the resilient connecting means having a tapered undercut portion in engagement with the tapered notched end of the projecting member and means for securing the connecting means to the projecting member to hold the tapered undercut lug in engagement with the tapered notched end of said projecting member.

4. In a device of the character described in combination with the lens holding means of an ophthalmic mounting, a member pivotally connected adjacent one of its ends to the lens holding means and having a grooved extension terminating in a tapered portion adjacent the end opposite the pivot, a spring member, a lug on the spring member having a tapered undercut portion engaging the tapered end of the grooved extension, said spring member having a portion thereof lying within the grooved extension and means for securing the portion of the spring within the groove and simultaneously securing the tapered end of the grooved extension and tapered undercut lug in interlocking engagement with each other.

5. In a device of the character described in combination with the lens holding means of an ophthalmic mounting, a member pivotally connected adjacent one of its ends to the lens holding means and having a grooved extension terminating in a notched portion adjacent the end opposite the pivot, a spring member, a lug on the spring member engaging the notched end of the grooved extension, said spring member having a portion thereof lying within the grooved extension and means for securing the portion of the spring within the groove and simultaneously securing the lug within the notched end.

6. In a device of the character described in combination with the lens holding means of an ophthalmic mounting, a spring anchor member connected to the lens holding means and having a grooved extension terminating in a tapered portion adjacent one end thereof and having an enlarged angle portion adjacent the pivot connection, said angled portion having a threaded recess therein, a spring member having a portion adjacent its end lying within the grooved extension and having an angled perforated end portion overlying the threaded recess in the angled portion of the anchor member, a lug on the spring member having a tapered undercut portion which engages and interlocks with the tapered end of the grooved extension when the spring is in position within the groove and a screw extending within the perforated end of the spring member and in the threaded recess to secure the end of the spring in the groove and hold the tapered

lug and tapered end in engagement with each other.

7. In a device of the character described in combination with the lens holding means of
5 an ophthalmic mounting, a spring anchor member pivotally connected to the lens holding means and having a grooved extension terminating in a notched portion adjacent one end thereof and having an enlarged angled portion adjacent the pivot connection,
10 said angled portion having a threaded recess therein, a spring member having a portion adjacent its end lying within the grooved extension and having an angled perforated end portion overlying the threaded recess in the angled portion of the anchor member, a lug on the spring member in engagement with the notched end when the spring is in position within the groove and a screw member
15 extending within the perforated end of the spring member and in the threaded recess to secure the end of the spring in the groove and hold the lug in engagement with the notched end of the grooved extension.
